WILLIAM T. HORROBIN, OF BENNINGTON, VERMONT.

Letters Patent No. 84,279, dated November 24, 1868.

IMPROVEMENT IN MOULDING-MACHINERY.

The Schedule referred to in these Letters Patent and making part of the same.

To all whom it may concern:

Be it known that I, WILLIAM T. HORROBIN, of the town and county of Bennington, in the State of Vermont, have invented certain new and useful Improvements in Moulding-Machinery, of which the following is a full, clear, and exact description, reference being had to the accompanying drawings, which make part of this specification, and in which—

Figure 1 represents a plan or top view of a moulding-machine, embracing my improvements, and

Figure 2, a vertical transverse section through the same, at the line *x x* of fig. 1.

Figure 3 represents a view in elevation of one of the arms which support the reversible follow-board, to which the patterns are attached, showing the devices for locking the follow-board and flasks in position.

Figure 4 represents a vertical transverse section through the same, at the line *y y* of fig. 3, and

Figure 5 represents a similar section at the line *z z* of fig. 3.

My invention relates to that class of moulding-machines in which the pattern is automatically separated from the mould; of which class my former patent, of February 28, 1865, is a representative; and the object of my invention is to provide means whereby the mould automatically may be separated from the pattern, to inspect it, and correct any defects, and the parts of the flask again be united, and caused to register truly.

The improvements herein claimed consist—

First, in a novel method of combining in a moulding-machine a reversible follow-board with a horizontally-moving mould-carriage, whereby either section of the flask may be removed from the follow-board, as desired.

Second, in a novel method of combining in a moulding-machine a reversible follow-board, and detachable moulds with locking-devices to hold the moulds upon the board while being reversed.

In order to carry out the objects of my invention, I mount upon a strong frame a bed-plate or carriage, to which a horizontal movement is given in either direction by suitable mechanism. A follow-board is mounted in suitable journals in a frame, moved up or down, at the will of the workman, by suitable mechanism. Patterns may be attached to each side of this follow-board, which can be revolved on its axis. The flask is placed on the follow-board, and the sand rammed in the usual way. A cover is then clamped on the flask, the follow-board and flask are raised, turned upside down, and then lowered upon the sliding carriage. Another flask may be placed on the upper side of the follow-board, and rammed, as before.

When the workman wishes to inspect the mould, he raises the follow-board far enough to lift the pattern above the mould, and runs the flask out from beneath the follow-board, in order to correct any defects in the mould. When his examination is completed, the mould may be run back under the follow-board. The parts

are made to register accurately, and are locked in their proper positions by suitable stops.

The accompanying drawings show one practical way of carrying out my invention. In this instance, A represents a strong frame, upon which the mechanism is mounted.

A carriage, C, slides in suitable ways in a bed-plate, B, on the frame, and is moved back and forth by a rack, *c*, and pinion D, on a shaft, *d*, operated by a crank, *d'*, these parts, for convenience, being arranged below the carriage.

A follow-board, E, has large studs, *e*, in its ends, mounted in bearings, *f*, in arms F, which move vertically endwise in suitable guides on the frame. These arms and the follow-board are raised or lowered by means of racks *g*, into which pinions G, on each end of a horizontal shaft, *g'*, take. This shaft is rotated by a hand-wheel, G', or other suitable device. The arms are held at any desired height by a pawl, *h*, which takes into a ratchet on the shaft *g'*, and prevents it from running backwards. A link-rod, *h'*, connects this pawl with a treadle, H, held up by a spring, *h''*, attached to the frame, which spring tends to keep the pawl engaged with the ratchet, but the workman can release it at any moment by depressing the treadle.

The follow-board is locked in a horizontal position, by means of spring-bolts, I, fig. 5, which slide beneath it on each side of the axle, and may be withdrawn by a thumb-bolt, *i*.

Screw-bolts J, fig. 4, pass horizontally through the studs *e*, for the purpose of locking the flask in position, being worked in or out, as required, by milled nuts *j*.

A flask, K, of any proper well-known construction, is placed upon the follow-board, and fastened by these screws. Patterns and flasks may be secured to each side of the follow-board. The flask, if heavy, may be fastened to the follow-board by vertical bolts and wedges.

When the flask K has been packed with sand, in the usual way, the cope L is put on, and locked by hasps *l* on it, which hook over staples *l* on the flask. The follow-board and mould may then be raised high enough above the carriage C to allow them to be revolved half round; the mould is then lowered upon the carriage C, and the flask released from the follow-board by unscrewing the bolts J. The follow-board is then raised again, thus removing the pattern from the mould, which is run out from beneath it by the carriage C, and inspected by the workman. When patterns are used on both sides of the follow-board, one workman may be filling the upper flask while the lower one is being inspected.

In case of any defect in the mould, the flask is again run in, and the follow-board lowered upon it, the accurate register of the parts being secured by the screws J.

The range of motion of the carriage is limited by suitable stops, which abut against the frame when the

carriage has reached the end of its traverse in either direction.

I am aware that White's English patent, No. 106, of 1858, shows a horizontally-moving carriage, in combination with vertical rammers, and do not therefore broadly claim, under this application, a horizontally-moving mould-carriage.

What I claim as my invention, and desire to secure by Letters Patent, is—

1. The combination, substantially as described, of

the reversible follow-board with the sliding carriage C, for the purposes set forth.

2. The combination of the flask with the reversible follow-board and the clamping-screws J, as and for the purpose set forth.

In testimony whereof, I have hereunto subscribed my name.
